UNITED STATES PATENT OFFICE

172,483

SHOULDER PIN

Beatrice H. Thompson, Los Alamos, N. Mex.

Application April 1, 1953, Serial No. 24,310

Term of patent 14 years

(Cl. D45—19)

To all whom it may concern:

Be it known that I, Beatrice H. Thompson, have invented a new, original, and ornamental Design for a Shoulder Pin, of which the following is a specification, reference being had to the accompanying drawing, forming a part hereof.

Figure 1 is a front elevation of a shoulder pin showing my new design.

Figure 2 is a perspective view thereof.

The essential features of my design reside in the portions shown in full lines.

I claim:

'The ornamental design for a shoulder pin, substantially as shown and described.
